Patented Aug. 1, 1922.

UNITED STATES PATENT OFFICE.

SEIHACHIRO NAKASORA, OF NILES, CALIFORNIA.

DIRECTION INDICATOR.

1,424,513.

Specification of Letters Patent. Patented Aug. 1, 1922.

Application filed November 11, 1920. Serial No. 423,367.

To all whom it may concern:

Be it known that SEIHACHIRO NAKASORA, a citizen of Japan, residing at city of Niles, in the county of Alameda and State of California, has invented new and useful Improvements in Direction Indicators, of which the following is a specification.

This invention relates to a direction indicator and particularly pertains to an indicator of the type shown in my Patent No. 1,353,128, issued September 14, 1920.

It is the particular object of the present invention to provide a direction indicator which embodies the use of a signal member adapted to be moved bodily to indicate a proposed turn of the vehicle to the right or left and the indicated stop, the particular object of the present invention being to produce an indicator of this type which is simple in construction and is so built as to insure that it may be operated without danger of getting out of order and with certainty at all times.

The present invention contemplates the use of a semaphore which may be rotated to the right or to the left in a horizontal plane, or may be turned downwardly to assume a position in a vertical plane, said semaphore being mounted upon a rigid supporting arm carrying means by which the semaphore may be readily manipulated.

The invention is illustrated by way of example in the accompanying drawings, in which—

Figure 1 is a view in vertical section and elevation showing the device with which the present invention is concerned.

Fig. 2 is a view of the bottom of the semaphore as seen in plan, showing the shifting means for operating the semaphore.

Fig. 3 is an enlarged view through the supporting arm as seen on the line 3—3 of Fig. 1.

Fig. 4 is a fragmentary view and plan showing one means by which the indicator might be secured to a vehicle wind shield.

Fig. 5 is a transverse view through the switch.

Referring more particularly to the drawings, 10 indicates one of the vertical posts of a vehicle wind shield. It is proposed to mount the present invention thereon, although it will be understood that it might be readily secured to the side of the vehicle

body or in any other position, or by any other means than shown in the drawings.

Reference being had to Fig. 4, it will be noted that the clamping bracket 11 is provided to secure the supporting arm 12 in adjustable relation to the wind shield post 10. This clamp structure comprises an arm 13, co-operating with a clamp arm 14, which means may be secured together by a clamp screw 15. The arm 14 carries a tubular support 16 through which the direction indicator arm 12 may be clamped. This clamping action is brought about by a screw 17. By means of this fitting, the position of the indicator relative to the wind shield may be determined, and at the same time horizontal adjustment of the indicator may be made. It is to be understood, however, that the supporting arm 12 extends at right angles to the longitudinal axis of the vehicle, and substantially parallel to the glass of the wind shield.

The supporting arm 12 consists of an outer tubular sleeve 18, within which a rotatable sleeve 19 is positioned. This sleeve is intended to fit snugly within the outer sleeve and is formed at its forward end with a shoulder 20. The rear end of the inner sleeve 19 is threaded as indicated at 21, to receive a switch housing 22. The end of this housing abuts against the end of the outer sleeve 19, and co-operates with the shoulder 20 to prevent longitudinal movement of the inner sleeve. Extending through the inner sleeve 19 is a shifting tube 23. This tube as shown more clearly in Fig. 2, is fitted at its outer end with an opposite member 24, carrying a gear rack 25. The shift tube is adapted to be slid longitudinally of the sleeve 19. This manipulation is brought about by an operating knob 26, which extends through a T shaped slot 27 in the outer sleeve 18, and a straight slot 28 in the inner sleeve 19. The ends of the slot 27 are slightly rounded and counterbored to receive the tapered end 29 of the knob. This knob is yieldably secured upon a central stem 30, and is held against the sleeve 18 by a spring 31. It will thus be evident that when the knob is moved to an extreme position in the slot, the tapered portion 29 will seat within the counterbore of the slot and will prevent accidental displacement of the knob or movement of the sleeve 19.

Rigidly secured to the outer end of the sleeve 19 is a horizontal plate 32 upon which is supported a semaphore box 33. This plate has a central opening 34, through which to receive a cylindrical stem 35 projecting from a bearing plate 36. This bearing plate is properly secured to the center of the semaphore box bottom and extends through the opening 34 to receive a gear 37. This gear is keyed to the stem 35 and will produce rotation of the stem and the semaphore box. The lower end of the stem is fitted to receive a lock nut 38. A series of ball bearings 39 are interposed between the plate 32 and a member 36, so that ease in rotation of the semaphore may be produced as the gear 37 is rotated by shifting action of the rack 25.

The semaphore box is rectangular in section and may be formed of any desired metal, in any dimensions required. The sides and top of the box are preferably cut away to form light openings in the shape of arrows as indicated at 40. The ends of the box are preferably cut away to form circular light openings 41, which will serve partially as a tail light when the vehicle is going straight ahead. Disposed over the light openings are sheets of transparent or translucent material such as celluloid or glass, and through which the light may shine to bring out the configuration of the light opening at night. In the day time, the difference in the color of the sides of the semaphore box and the translucent screens 42 will make the signals visible.

Secured to the bottom of the lamp house is a clamp 43 carrying socket 44 of an incandescent lamp 45, by which the semaphore is illuminated. One wire of an electric circuit is grounded as indicated at 45, while the other wire 46 is led through a tube 47. This conduit extends entirely through the shifting tube 23 and terminates within the switch housing 22. The switch may be of any desired construction, although in the present instance it is shown as having a rotating switch blade 48, which is operated by means of a stem 49 extending out through the end of the switch housing and fitted with a knob 50. The switch blade may be brought to engage contact members 51 and 52, to complete a circuit through the conductors 45 and 46 to the source of electric supply, as indicated at 53.

In operation of the present invention, the device is assembled as shown in Fig. 1, and may then be suitably mounted upon a vehicle. Normally the knob 26 is disposed at the intersection of the longitudinal and transverse legs of the slot 27. When in this position the semaphore will extend with its longitudinal axis at right angles to the longitudinal axis of the supporting arm 12. The circular light opening 41 in the oppo-

site ends of the semaphore housing will thus be visible at the front and the rear of the vehicle, while the arrows on the opposite sides of the housing will both point forwardly. In the event that the driver contemplates a turn to the right, he draws the knob 26 rearwardly along the slot 27, and this will act to shift the rod 23 and the gear rack 25 in a manner to swing the semaphore to the right and cause the arrows on the two sides to both point to the right. In the event that a turn is to be made to the left, the knob is shifted to the extreme forward end of the slot 27 to produce a half turn of the semaphore, and cause both arrows to point left. It will be understood of course that this movement will be reversed by placing the rack 25 upon the opposite side of the gear 37, and it is also to be understood that other means might be connected with the shifting member 23 to produce rotation of the semaphore without departing from the spirit of the present invention. When the vehicle intends to stop, the knob 26 is brought to the intersection of the longitudinal and transverse portions of slot 27, and is thus turned downwardly. The knob pin 30 will thus encounter the side of slot 28 in the inner sleeve 19, and will rotate this sleeve a quarter of a turn. As will be seen in Fig. 1, the top of the semaphore is formed with a character similar to that on the sides, when the driver desires to signal that he is about to stop the knob 26 is turned to engage the slot 27 and turning the sleeve 19 a quarter of a turn which is transmitted to the semaphore and turns the same so that the arrow formed at the top thereof appears vertical. At night the semaphore may be illuminated by the lamp 45.

It will thus be seen that the invention here disclosed is formed of few parts compactly assembled and readily operated in a manner to prevent them from becoming inoperative due to vibration or other movement incident to the operation of the vehicle upon which they are mounted.

While I have shown the preferred form of my invention, it will be understood that various changes in the combination, construction and arrangement of parts may be made by those skilled in the art, without departing from the spirit of the invention as claimed.

Having thus described my invention, what I claim and desire to secure by Letters Patent is:

1. A direction indicator comprising an outer fixed sleeve, an inner sleeve rotatable relative to the outer sleeve, and held against longitudinal movement, a mounting plate secured to the end of said inner sleeve and normally operated in a horizontal plane, a semaphore box pivotally disposed upon said mounting plate adapted to rotate horizon-

tally, means extending through said inner sleeve for producing horizontal rotation of the semaphore box, and an operating means by which the horizontal rotation of the sema-

5 phore box will be brought about, or the vertical rotation of the inner sleeve and the box.

2. A direction indicator comprising an outer fixed sleeve, an inner sleeve rotatable 10 relative to the outer sleeve, and held against longitudinal movement, a mounting plate secured to the end of said inner sleeve and normally operated in a horizontal plane, a semaphore box pivotally disposed upon said 15 mounting plate adapted to rotate horizontally, means extending through said inner sleeve for producing horizontal rotation of the semaphore box, an operating means by which the horizontal rotation of the sema- 20 phore box will be brought about, or the vertical rotation of the inner sleeve and the box, and means for illuminating the semaphore box.

3. A direction indicator comprising an 25 outer sleeve, means for adjustably securing said sleeve in rigid relation to a vehicle body, an inner rotatable sleeve held against longitudinal movement relative to said outer sleeve, an extension plate secured to the end 30 of said rotatable sleeve, a rectangular semaphore box, rotatable support upon said plate for horizontal movement, and shifting means extending through said rotatable sleeve, means operated by said shifting means for 35 producing horizontal rotation of said semaphore box, and an operating knob adapted

to be moved longitudinally of the outer sleeve to actuate said shifting means, and adapted to be swung transversely of the sleeve to produce rotation of the rotatable 40 sleeve and a semaphore box carried thereby.

4. In a vehicle signal device, a fixed bracket a supporting arm extending therefrom, a rotatable and a reciprocal sleeve supported by the arm, a semaphore box pivotally supported at the end of the supporting arm, means connected to the semaphore and the reciprocal sleeve for rotating the former on a horizontal plane when the sleeve is reciprocated and means permitting vertical rotation of the semaphore when the rotatable sleeve is rotated.

5. In a device of the character described a semaphore, a pivotal support therefor, a rotatable and a reciprocal sleeve connected 55 to the semaphore, and a single means for actuating either of the sleeves for producing either horizontal rotation or vertical rotation of the semaphore.

6. A direction indicator comprising a 60 fixed bracket, a rotatable sleeve supported thereby, a semaphore supported at the outer end of said sleeve for rotation in a plane parallel to the longitudinal axis of the sleeve, a second sleeve mounted in the first named 65 sleeve and adapted to be reciprocated for producing rotation of the semaphore in a horizontal plane, and means for rotating the first named sleeve to produce rotation of the semaphore in a vertical plane.

SEIHACHIRO NAKASORA.
